UNITED STATES PATENT OFFICE.

SIDNEY LOUIS WALTER MERLIN, OF PARIS, FRANCE.

TYPE-WRITING MACHINE.

SPECIFICATION forming part of Letters Patent No. 708,821, dated September 9, 1902.

Application filed July 26, 1900. Renewed August 6, 1902. Serial No. 118,658. (No model.)

To all whom it may concern:

Be it known that I, SIDNEY LOUIS WALTER MERLIN, a subject of the Queen of Great Britain, residing at Paris, France, have invented 5 certain Improvements in Type-Writing Machines, of which the following is a specification.

This invention relates to improvements in the carriages of type-writing machines, where-

10 by the making of corrections while writing is greatly facilitated; and it belongs to that class of devices for effecting the object desired wherein the platen cylinder or roller is moved or shifted endwise to a limited extent.

15 The present invention provides a novel means for shifting the platen-roller endwise, and with it the paper; and it also provides means for regulating the angular movement of said roller.

20 In the accompanying drawings, which illustrate an embodiment of the invention, Figure 1 is a fragmentary sectional view of the platen-roller and adjusting mechanism. Fig. 2 is a plan of the same, showing both ends of said roller. Fig. 3 is a vertical section taken in the plane indicated by the line x^3 in Fig. 1.

A designates the platen cylinder or roller, covered with india-rubber, as usual, and B is the shaft or spindle on which said roller is 30 secured in any convenient manner—as, for example, by means of end plates a a' , screwed to the roller and secured to the shaft or spindle by set-screws. The spindle B has a sliding and rotating bearing in the frame C of the carriage, and on its end is secured a milled 35 thumb-wheel b , as usual.

On the spindle B is formed a boss c , exterior to the frame C, and this boss is screw-threaded to receive a nut d , milled so that it 40 may be conveniently turned by the thumb and finger. This nut d bears on the outer face of the frame C, and by turning it in the proper direction the spindle B and roller A may be moved endwise in one direction, to the left as 45 the parts are represented in Figs. 1 and 2, a spring d' serving to move the roller in the opposite direction when permitted by the nut d . The spring d' may be on the spindle B, between a nut d^2 thereon and the frame C. 50 A nut similar to the nut d might, however, be substituted for the spring for shifting the roller A to the right.

It will be readily understood that by the means above described the roller A, carrying the paper with it, may be shifted lengthwise 55 to as slight an extent as may be required to bring the letter to be corrected opposite to a division of the scale or into any position it is desired that it shall occupy. To permit of properly alining the sheet, the device now to 60 be described is employed.

I form a reduced screw-threaded boss e on a projecting part of a boss on the roller A (here shown as on the plate a) to receive a milled nut f , which serves to clamp an arm h , 65 mounted to swing on a journal formed on the boss of the roller, up to a shoulder g , thereby fixing said arm to the roller. The arm h carries at its free end an adjustable limiting-screw q , provided with lock-nuts r and s , and 70 said arm is adapted to vibrate between the frame C and a lug k on a pendent bracket i , secured to the frame C.

The operation of this device is as follows: The sheet of paper being placed on the roller 75 A so that the line of writing registers exactly with the scale, the milled nut f is loosened and the arm h lowered into contact with the lug k . The nut f is then tightened, so as to clamp the arm h to the roller, and the 80 latter rotated forward until the head of the screw q impinges on the under side of the frame C. This will bring the line of writing exactly to the position required. The object of the screw q is to regulate the extent 85 of rotation of the roller A to suit the line-spacing of the machine.

I am aware that it is not new, broadly, to provide a type-writing machine with means for moving the platen-roller thereof endwise 90 to bring a point in the printed line exactly to the printing-point, and this I do not claim. So far as this part of the present invention is concerned the novelty lies in the special means employed.

95 It may be proper to state that the lug or limiting-stop k will be long enough to permit the roller A to be shifted endwise to the maximum extent desired without carrying the arm h beyond the end of said lug. The other limiting-stop for the arm h may be the frame C itself or any part secured to it.

Having thus described my invention, I claim—

1. In a type-writing machine, the combination with the frame, and the platen-roller, its boss, and its spindle mounted rotatively in said frame, of an arm mounted on and adapted to swing about said boss, stops to limit the swing of said arm, and means for clamping said arm to the platen-roller, substantially as set forth.

2. In a type-writing machine, the combination with the frame C, the spindle B mounted rotatively therein, the cylinder A, mounted on said spindle and provided with a screw e, and the boss of said cylinder, of the clamp-nut f on said screw, the arm h, hung on the boss of the cylinder and adapted to be clamped fast thereto by the nut f, the bracket i k, and the screw q in said arm h, substantially as and for the purpose set forth.

3. In a type-writing machine, the combination with the frame C, and the platen-roller A, mounted rotatively therein and slidably longitudinally, of means for moving the said roller endwise with precision, and means for limiting the extent of its rotation for

spacing purposes, said means comprising an arm mounted to swing about the axis of the roller A, means for clamping it fast to the roller, and means for limiting the extent of its movement when so clamped fast, substantially as set forth.

4. In a type-writing machine, the combination with the frame C, the spindle B, mounted slidably and rotatively therein, the platen-roller A fixed on said spindle, and means for shifting said roller endwise in the frame, of the arm h, adapted to swing about the axis of the platen-roller, the nut for clamping said arm to the roller, the screw q in said arm, and stops for limiting the extent of swing of said arm when clamped to the roller, substantially as set forth.

In witness whereof I have hereunto signed my name in the presence of two subscribing witnesses.

SIDNEY LOUIS WALTER MERLIN.
